CLAIM

The ornamental design for a miniature hair trimmer housing, as shown and described.

DESCRIPTION

FIG. 1 is a perspective view of one embodiment of a miniature hair trimmer housing of the present invention;

FIG. 2 is a front view of the miniature trimmer of FIG. 1;

FIG. 3 is a right side view of the miniature hair trimmer housing of FIG. 1;

FIG. 4 is a left side view of the miniature hair trimmer housing of FIG. 1;

FIG. 5 is a rear view of the miniature hair trimmer housing of FIG. 1;

FIG. 6 is a top view of the miniature hair trimmer housing of FIG. 1;

FIG. 7 is a bottom view of the miniature hair trimmer housing of FIG. 1;

FIG. 8 is a perspective view of an alternate embodiment of the miniature hair trimmer housing of the present invention;

FIG. 9 is a front view of the miniature hair trimmer housing of FIG. 8;

FIG. 10 is a right side view of the miniature hair trimmer housing of FIG. 8;

FIG. 11 is a left side view of the miniature hair trimmer housing of FIG. 8;

FIG. 12 is a rear view of the miniature hair trimmer housing of FIG. 8;

FIG. 13 is a top view of the miniature hair trimmer housing of FIG. 8; and,

FIG. 14 is a bottom view of the miniature hair trimmer housing of FIG. 8.

The broken line showing of the switch, contacts, housing interior, screw hole, interface and groove is for illustration purposes only and forms no part of the claimed design.
